UNITED STATES PATENT OFFICE

RAYMOND C. CUNNINGHAM, OF SEATTLE, WASHINGTON, ASSIGNOR TO HINCHER
PAPER BOX CO., OF SEATTLE, WASHINGTON, A CORPORATION OF WASHINGTON

BOX-WRAPPING DEVICE

Application filed September 12, 1927. Serial No. 219,018.

My invention relates to box-wrapping machines; and its object is to provide a machine of this character which will simplify and lessen the cost of producing covered boxes.

5 The invention consists in the novel construction, adaptation and combination of devices hereinafter described and claimed.

In the accompanying drawing,—

Figure 1 is a transverse vertical section of 10 a form block and associated parts of a box-wrapping machine with regulating devices embodying the invention applied thereto; Figs. 2 and 3 are fragmentary plan views of Fig. 1 with the regulating devices shown in 15 different relative positions; Fig. 4 is a diagrammatic view, shown in perspective, of a box blank of the flange or extension-bottom type and the paper wrapper therefor; Fig. 5 is a perspective view of a box-blank such as 20 illustrated in Fig. 4 having its sides secured by means of corner stays; and Fig. 6 is a view similar to Fig. 1 and including portions of the machine frame and mechanism for actuating the box-forming and box-wrapping devices illustrated in Figs. 1, 2 and 3.

It has hitherto been the practice for flange-box wrapping to secure the side and end wall elements S and E of a box blank together at the various corners by pasting thereto pieces 30 of paper P, as shown in Fig. 5, for the purpose of retaining the blank in the form of a box. The setting up and staying the box blank as above explained has been effected by a special machine, or manually, prior to putting it 35 into the machine which performs the wrapping. With the present invention, however, the box is not stayed, is placed in the machine with the extension bottom B glued thereto as represented in Fig. 4 above the 40 wrapper or covering paper D, which is utilized for securing the parts of the blank in relatively box form and obviates the use of stays or other corner fastening means as heretofore.

45 The present invention, eliminating the necessity of using box stays, or other fastening means ancillary or supplemental to the covering, facilitates the manufacture of wrapped boxes of the extension edge type, lessens the 50 labor, and reduces the cost of production.

The wrapping machine in which my invention is employed is provided with a form block 5 secured to the lower end of a vertically movable plunger 6, said form-block being arranged to cooperate with a work-supporting block 7 which is secured upon the upper end of a vertically movable lower spindle 8.

Also provided in said machine for reciprocating movement transversely thereof are 60 horizontal wing-bars 10 arranged parallel, or nearly so, with the side surfaces of the blocks 5 and 7. Said wing bars 10, one at each side of the form blocks 5 and 7 (Fig. 1) are each arranged for the reciprocating movement above referred to by well known means such as illustrated in Fig. 6 and may be described as follows: Rigid with each wing bar 10, but one is shown in Fig. 6, are depending arms 30 from which extend horizontal 65 guide rod elements 31 through ways such as 32 provided in a member 33 of the machine frame. The guide elements 31 are each equipped with a stud 34 extending through a slot 35 of a lever arm 36 extending upwardly 70 from a rocker shaft 37 mounted in hangers such as 38 which extend downwardly from the respective frame member 33. The rock shaft above referred to has keyed or otherwise secured thereto a crank arm 39 which is 75 operatively connected by a connecting rod 40 with an arm 41 of a vibratory lever 42 which is fulcrumed at 43 to the machine frame. Another arm 41' of said lever is in like manner connected by a connecting rod 40' with 80 mechanism (not shown) similar to what I have described above for imparting reciprocating movement to the other wing bar shown in Fig. 1 but which, for lack of space, is 85 omitted from Fig. 6.

90 The vibratory movement to the aforesaid lever 42 is accomplished through the provision of a third arm 42' to the lever to carry a stud, indicated by 44, which tracks in a cam slot 45 of a cylindrical drum 46 which is rotated with a vertical shaft 47 which is driven through the medium of a gear wheel 48 and worm 49 from a shaft 50 which is driven as by means of a motor (not shown) through a power belt 51 and pulley 52 indicated by 95 100

dotted lines in Fig. 6. The above described parts which constitute the mechanism whereby the wing bars 10 are supported, reciprocated and operated is old in the art of wrapping boxes, as hitherto unprovided with flanges or edge extensions.

Said wing bars have adjustably secured thereto brackets 11 which serve to support holders 12 for corner lap-plates 13. Said holders are pivotally connected by means of pins 14 to the respective brackets, permitting the free ends of the lap-plates to be swung slightly outwardly in opposition to springs 15 (Fig. 1) to accommodate the inequalities in the lengths of boxes, differences in thickness of the cover paper and also afford pressure against the cover laps, as D² when the lap-plates traverse such laps to effect pasting the same to underlying parts of the wrapper or cover paper.

All of the parts above referred to are old in box wrapping machines and their functions and manner of operating well understood.

According to the present invention, I provide means, actuated by movements of the wing bars 10 to regulate the box, whereby the side portions D¹ of the paper covering D are brought against the respective box side wall elements S and the latter, in turn, against the block 5, thus positioning the lap extensions D² of the respective side-wrapper portions so that the lap-plates 13 will effect the turning of the lap extensions D² about the respective corners of a box and against the cover end-flaps D³ for pasting the laps D² thereto while the box ends E are being brought by the travel of the lap-plates against the block form 5.

As shown in the drawing, my invention comprises a plurality of regulating or presser members, one for each corner of a box, each of said members consisting of a horizontal rod element 16 disposed in the direction of the travel of the associated wing bar 10,—that is, at right angles to the side surfaces of the form-block 5,—the rod extending through guide ways provided in flange elements 17 of an attachment 18 of the respective holder 12.

Toward said form-block the rod 16 is bent at 19 upwardly as an arm 20. The outer end of the rod element 16 of each presser member is connected to a spring 21 whose other end, as shown in Fig. 1, is connected to a flange element 17 of the respective attachment. Thus arranged, a spring 21 serves to yieldably retain the associated member in its innermost position as limited by a set-collar 22 provided upon the rod element 16 of the respective member.

Assume that the wrapper as D has been pasted to the extension bottom B of a box form, unprovided with stays, as P in Fig. 5, and that paste has been applied to the mar-

gins of the flaps D¹, D³, and also to the laps D² and that the assembly of the above named parts is positioned in the machine with the box bottom and the central portion of the wrapper engaged between the blocks 5 and 7 of the machine.

Thus arranged, when said blocks descend with the work, the rolls (not shown) of the machine act in a known manner to press the wrapper flaps D¹ and D³ about the flange portions of the extension bottom B and against the side and end wall elements S and E and pushing them against the respective side and end surfaces of the form block 5.

The side and end walls of the box and the flaps pasted thereto are thus brought into substantially the relation with respect to the form block in which they are shown in Fig. 1 with regard to the side walls S and the associated flaps D¹ of the wrapper. The wing bars 10 then move toward the block 5 causing the respective lap-plates 13 and the regulators 16—20 to advance, to again push the side walls S against the respective sides of the block as represented in Fig. 2 with respect to one side of a box.

Continued advance movements of the wing bars 10 carry the lap-plates 13 therewith to swing each of the laps D² from a position such as indicated in Fig. 2 to that in which it is indicated in Fig. 3 with respect to one corner; meanwhile the regulators are holding the box sides firmly against the form block and the lap plates have traversed the respective laps to effect the pasting of the same to the wrapper flaps D³ at the ends of the box, whereby, the wrapper itself serves to hold the box in shape without the use of corner stays or other fastening means. It is to be noted that the springs 21 yieldably hold the regulators in positions to perform their duty of holding the box side walls firmly against the form block while the lap-plates 13 are accomplishing the securing of the wrapper in condition to hold the box in shape.

Furthermore, in the withdrawal of the lap-plates in the return movement of the wing bars, the springs 21 provide pressure through the arms 20, to retain the flaps D¹ and side walls S against the form block 5, to effectively, during the return passage and drag of said plates over the laps, eliminate any possibility of box side wall strain to said adhesive engaged turned over laps.

While I have shown and described the invention as applied to a box with an extension bottom, it is done for illustrative purposes only and not restrictive as the invention is equally applicable for use with other types of wrapped paper-boxes.

What I claim, is,—

In a machine for covering boxes, the combination with a form block having a box blank and side and end wall securing flaps

mounted thereon, of reciprocatory wing bars, lap pressing plates mounted upon said wing bars and arranged to press projecting portions of the side wall flaps over the end wall flaps and spring regulated rods rendered operable by the travel of said wing bars for pressing and holding the side walls and flaps of the box blank against the form block, prior to and during the operation of the lap pressing plates.

Signed at Seattle, Washington, this 16 day of August, 1927.

RAYMOND C. CUNNINGHAM.
